UNITED STATES PATENT OFFICE.

JOSEPH A. BECVAR, OF TUXEDO PARK, NEW YORK.

CARNATION-HOLDER.

1,053,146.

Specification of Letters Patent. Patented Feb. 18, 1913.

Application filed October 16, 1911. Serial No. 654,958.

To all whom it may concern:

Be it known that I, JOSEPH A. BECVAR, a citizen of the United States, residing in Tuxedo Park, county of Orange, and State of New York, have invented a certain new and useful Carnation-Holder, of which the following is a specification.

This invention is a device of simple and efficient construction for supporting and 10 guiding growing plants and flowers, such as carnations.

To this end the invention embodies an improved collapsible structure which can be readily assembled, and can also be quickly 15 taken apart and compactly stored when not in use, or compactly boxed for shipment.

In the embodiment of the invention herein described and claimed, I provide a plurality of separate members or units, which 20 may be readily attached together to form the complete device, and, also, be separated when desired.

Other features of the invention will be apparent from the hereinafter detailed description.

In the accompanying drawings, I have illustrated one practical embodiment of the invention, but the construction shown therein is to be understood as illustrative, only, 30 and not as defining the limits of the invention.

Figure 1 is a perspective view of the assembled device mounted in a bench, and Fig. 2 is a partial longitudinal sectional 35 elevation of the device taken centrally of the structure.

Referring to the drawings, A are the end members composed of wire uprights or posts a, and the cross tie wires b. Uprights a are 40 bent at their bottoms in the shape of a loop or eye a', which form feet or supports. Each of the upper tie wires b is provided with a supporting hook or hooks e for a purpose to be presently described.

B is a top member composed of the longitudinal wires c, and suitably spaced transverse tie wires d, forming a substantially 45 rectangular shaped construction, the end wires d of which are adapted to be seated in the supporting hooks e, whereby said top member B is supported, substantially, 50 by the end members A.

Intermediate the top and bottom of the end members A are the longitudinal tie 55 members or racks C, composed of the side wires c' and cross wires d'. The ends of

the side wires c' are provided with hooks f which rest on the tie wires b, and embrace the uprights a, whereby said longitudinal tie members C are supported, substantially 60 by the end members A, but serve to give rigidity to said end members. It will be noted that the cross or transverse wires d separate the top and longitudinal members into the spaces which are to be occupied by 65 the plants.

The longitudinal members C, as well as top member B, are stiffened against buckling, or partly supported, by the vertical wire uprights g, extending between them, 70 said wires g being provided with hooks h, or equivalent means, for properly securing them in position on the longitudinal wires c and c'. Wires g, it will be observed, may be readily attached or detached from top 75 member B and longitudinal members C, by reason of the slight spring or yielding action of said wires and members. The two lower vertical wires g are provided with feet a² similar in construction to feet a'. 80

I have shown the structure mounted or positioned in a "bench" or box D, filled with loam or soil E, and in which the plants, such as carnations, are grown. It will be apparent that the device may be extended as 85 to length or width without departing from the principle or spirit of the invention, and that a plurality of the devices may be used in a single bench. The end members A are preferably provided with a cross piece i 90 positioned at such height as to rest on the soil when the device is mounted in the bench.

From the foregoing description of the structure of the device it will be apparent 95 that, as a whole, it is composed of five separate members, to wit, the two end members A, the top member B and longitudinal tie members C, and, in addition, the intermediate supports g, and that the said members 100 may be readily assembled together, or detached from each other, without necessitating the employment of any fixed connections or attachments.

The manner of using the device, as well 105 as its function, will be apparent from the foregoing description, but it may be described, briefly, as follows. The carnations are planted as usual, and so positioned apart that a single plant will occupy the center of 110 the substantially square or rectangular spaces formed by the longitudinal wires c

and cross wires *d*, though, if desired, the plants may be so positioned that only every other space is occupied by a plant. This will be dependent somewhat, of course, on 5 the dimensions of the said spaces and the particular character of the plant to be grown. As the plants develop they are trained to grow upright in the alining spaces.

10 It will be apparent that no particular skill is required to manipulate the device, that it is economical to manufacture, and that it is particularly well adapted to perform its intended functions.

15 Having thus fully described the invention, what I claim as new, and desire to secure by Letters Patent is:—

1. In a collapsible carnation support, the combination of end members separate from 20 the carnation bench and each consisting of a substantially rectangular wire frame work having two side members, the lower ends of which form supporting legs which are insertible in the earth of a carnation 25 bench, supporting means near the top of each end member, a top member consisting of a wire frame work detachably carried by said supports, a plurality of unitary racks substantially rectangular in shape positioned below said top member, means on 30 either end of said racks for detachably securing the racks to the end members, spacing wires in said top member and racks whereby vertically alining spaces are 35 formed in said rack and top members, and

separate tie rods extending between each pair of adjacent racks, and the bottom rack and the ground, said tie rods having hook members for detachably connecting them to the lateral reaches of the top member and 40 the racks.

2. In a collapsible carnation support, the combination of four corner uprights, means for retaining the two uprights at either end of the device in fixed, spaced relation where- 45 by oppositely placed end portions are formed, and unitary frames of substantially rectangular shape extending from one end portion to the other, said frames being detachably supported by the spacing means for the 50 end portions.

3. In a collapsible carnation support, the combination of four corner uprights, means for retaining the two uprights at either end of the device in fixed, spaced relation where- 55 by oppositely placed end portions are formed, unitary frames of substantially rectangular shape extending from one end portion to the other, said frames being detachably supported by the spacing means for 60 the end portions, and a tie unit adapted to be positioned in pairs between each pair of racks, and the bottom rack and the ground.

In testimony whereof I have signed my name to this specification in the presence of 65 two subscribing witnesses.

JOSEPH A. BECVAR.
